STOPPER FOR DRAIN OUTLETS

Carl G. Hicks, Chicago, Ill.

Application January 18, 1936, Serial No. 59,675

9 Claims. (Cl. 4—293)

This invention relates to that type of stoppers for the drain outlet of household sinks, bath tubs and the like, consisting of a central main member of metal or like rigid material and marginal border member of flexible material such as india rubber, and this improvement has for its main object:

To provide a structural formation of a two part closure cover for the drain outlets of the type above referred to, wherein a substantial non-rickable connection between the two portions of the device is attained in an effective and economical manner, as will hereinafter more fully appear.

In the accompanying drawing:

Fig. 1 is a bottom plan illustrating the preferred arrangement of parts in this improvement.

Fig. 2 is a central section of the same on line 2—2, Fig. 1.

Fig. 3 is a bottom plan of the device, showing a modified form of the notched formation shown in Fig. 1 omitted.

Like reference numerals indicate like parts in the different views.

In its preferred form, as shown in the drawing, this improvement in drain outlet stoppers or covers comprises a rigid central body 1 of sheet metal of a concavo-convex shape, the margin of which is formed in the manner hereinafter described adapted to effect a substantial non-leaking attachment of an associated annular border member 2 of flexible material such as india rubber.

The main and material feature of this improvement involves a formation of the border portion of the central main body 1 aforesaid, with a plurality of annular return bends or folds 3 and 4, the configuration of a flattened letter S, with the intermediate fold 3 in contact with the bottom face of the main body 1, and with the lower fold 4 in spaced relation to the aforesaid intermediate fold 3, in order to provide a space for the reception of the inner portion of the annular elastic border member 2 aforesaid, with the same held in place by a closure of the fold 4 in a direction towards the fold 3 aforesaid.

Another material feature of this improvement comprises a formation of the aforesaid lower fold 4 of the plurality of bends and folds aforesaid, with a series of marginal notches adapted to provide a like series of independent marginal flat prongs 5 that are adapted to provide a more ready manipulation in the assembly of the device, where the main body is formed of sheet metal or plate metal of an extra thick gauge, when greater rigidity of the main body 1 is desired.

Still another feature of this improvement involves the formation of the outer margin of the annular and flexible outer member 2 of the device, with an orificed projecting portion or extension 6 for the purpose of a ready handling of the device, as well as for hanging up thereof when not in use.

Having thus fully described my invention, what I claim as new, is:—

1. A stopper for drain outlets, comprising a central main body member of sheet metal having a concavo-convex formation with its margin formed with a plurality of return bend folds, and an annular outer plate member of india rubber or like flexible material, the inner margin of said outer annular member being arranged and held in place in a recess between the intermediate and the lowermost of the aforesaid folds.

2. A stopper for drain outlets comprising a central main body member of sheet metal having a concavo-covex formation with its margin formed with a plurality of return bend folds, the lowermost said fold being notched to provide a plurality of outwardly extending prongs, and an annular outer plate member of rubber or like flexible material, the inner margin of said annular member being arranged and held in place in a recess between the intermediate and the lowermost of said folds.

3. A suction type stopper for drain outlets, comprising a central main body member of sheet metal having a concavo-convex formation with its margin formed with a plurality of return bend folds, the lowermost said fold being notched to provide a plurality of outwardly extending prongs, and an annular outer plate member of rubber or like flexible material, the inner margin of said annular member being arranged and held in place in a recess between the intermediate and the lowermost of said folds, the said annular member being provided with a tab-like extension on its outer border whereby the said annular member may be flexed to admit air or water to the drain and break the suction of the stopper.

4. A stopper for drain outlets comprising a central main body member of sheet metal having a concavo-convex formation with its margin formed with a plurality of return bend folds, the lowermost said fold being notched to provide a plurality of outwardly extending prongs, and an annular outer plate member of rubber or like flexible material, the inner margin of said annular member being arranged and held in place in a recess between the intermediate and the lowermost of said folds, said annular flexible member

having an orificed tab-like extension on its outer border.

5. A suction type sink stopper comprising a metal disc having an integrally channeled edge portion and a rubber annulus having its inner peripheral region seated and clamped in said channeled portion.

10. A suction type sink stopper comprising a metal disc having an integrally channeled edge portion and a rubber annulus having its inner peripheral region seated and clamped in said channeled portion, said annulus having a suction breaking tab extended therefrom.

15. A suction type sink stopper comprising a concavo-convex sheet metal disc having an integrally formed channeled portion in its peripheral edge, and an annulus of rubber or like flexible material clamped at its innermost peripheral edge portions in said channeled portion of the disc.

20

8. A suction type sink stopper comprising a concavo-convex sheet metal disc having an integrally formed channeled portion in its peripheral edge, and an annulus of rubber or like flexible material clamped at its innermost peripheral edge portions in said channeled portion of the disc, said annulus having a tab-like extension for flexing the latter to break the suction of the stopper.

5

10. A suction type sink stopper comprising a concavo-convex body member having its outer edge portion bent back upon itself to form a return bend providing a channeled portion opening outwardly of the said edge and having an annular apron of flexible material clamped into the said channeled portion, the said apron having a manually engageable extended portion for flexing the same to break the suction of the stopper.
